BUILDING AIR MONITOR

James G. Phillips, Santa Fe, N. Mex., assignor to Eberline
Instrument Corporation, Santa Fe, N. Mex.

Filed Feb. 26, 1965, Ser. No. 83,989

Term of patent 14 years

(Cl. D16—2)

FIG. 1 is a perspective view of a building air monitor showing my new design;

FIG. 2, a side elevation;

FIG. 3, a top plan view;

FIG. 4, a rear elevation; and

FIG. 5, a bottom plan view.

I claim:

The ornamental design for a building air monitor, as shown.
